UNITED STATES PATENT OFFICE.

ANKER PETERSEN, OF WINTHROP, MASSACHUSETTS.

BRAIDING-MACHINE.

1,241,550.

Specification of Letters Patent.

Patented Oct. 2, 1917.

Application filed March 25, 1916, Serial No. 86,754. Renewed February 23, 1917. Serial No. 150,621.

To all whom it may concern:

Be it known that I, ANKER PETERSEN, a citizen of the United States, and resident of Winthrop, in the county of Suffolk and State of Massachusetts, have invented new and useful Improvements in Braiding-Machines, of which the following is a specification.

This invention relates to rotary braiding machines, and particularly to the thread carriers and the means for supporting and controlling the same. In Letters Patent No. 1,105,452, issued to me July 28, 1914, there is shown a form of thread carrier having a roller at its inner end and a roller at its outer end by which the carrier is supported at both its inner and its outer ends upon positively driven pairs of rollers mounted on a revolving frame. One of the principal objects of this invention is to eliminate the inner pair of supporting rollers altogether and the positive drive of the outer rollers, and to take the weight off the outer pair of supporting rollers which are used in the present invention merely to drive the thread carrier in its circular path about the machine. The roller at the inner end of the thread carrier in my new construction runs on the margin of a disk which is preferably rotary and travels in the opposite direction to the thread carrier and in the same direction as the strands which are passed over and under the thread carriers.

These and other features of the invention will be hereinafter more fully described and particularly pointed out in the claims.

In the accompanying drawings which show one embodiment of the invention,—

Figure 1 is a vertical section of such parts of a braiding machine as are necessary to illustrate the invention;

Fig. 2 is a plan view, partly broken away, of certain of the parts shown in Fig. 1; and

Fig. 3 is an elevation of the outer end of one of the thread-mass carriers.

For a description of the general type of machine to which the invention is applicable, reference may be had to the aforesaid patent, and it will only be necessary in the present specification to describe such parts

of the machine as will serve to make clear the novel features and their relation to the machine as a whole.

Referring to the drawings, 1 represents the frame of the machine, preferably made spider shaped and provided with a central hub 2 which supports a central tubular shaft 3, at the top of which the fabric is formed. The shaft 3 is surrounded by a sleeve 4, which is rotatable on the shaft 3 and has secured to it a bevel gear 5, which rotates on the upper face of the hub 2. The fabric passes down through the hollow shaft 3 to an idler roller 6 mounted on hub 2, and thence passes to the take-up mechanism (not shown). A driving shaft 7, journaled in bearing bracket 8, secured to a ring 9 which forms part of the frame, is provided at its inner end with a pinion 10 which meshes with bevel gear 5.

Upon sleeve 4, above the bevel gear 5, is the revolving frame 11 which supports the strand guides (not shown), and is revoluble on sleeve 4. The frame 11, which may be termed the main revolving frame, is provided with a bevel gear 12 on its under side engaging pinion 10. Thus the parts carried by frame 11, and those carried by sleeve 4, to which gear 5 is secured, are caused to revolve in opposite directions.

Above the frame 11, is a disk 13, fast to sleeve 4, to which are secured concentric annular rims 14, 15 and 16 connected by radial arms 17, the inner rim 14 being mounted on disk 13. In each of the segmental spaces between rims 15 and 16, there is journaled a pair of idler rollers 18 and 19 for driving the thread carriers hereinafter described. The disk 13 with its rims and radial arms may be termed the roller frame.

Another disk 20 is mounted to revolve on hollow shaft 3 above sleeve 4. The disk 20 is provided with a bevel gear 21 on its under side and the disk 13 is provided with a bevel gear 22 on its upper side. Bevel pinions 23, mounted on a bracket 24 fixed to the hollow shaft 3, work between gears 21 and 22 causing the disk 20 to be rotated in the opposite direction to disk 13 and the thread carriers driven thereby, and in the same direction as the strand guides (not

shown) mounted on the revolving frame 11. Thus the disk 20 moves in the same direction with the strands t' and prevents rubbing and chafing of the strands, while the rollers 5 27 roll freely over the strands. For certain classes of work, and in small size machines it will be found possible to mount the disk 20 stationary on the shaft 3.

A series of thread carriers 25, each carrying a cop or mass of thread 26, are mounted in the several segmental spaces between rims 14 and 15 and arms 17. At the inner end of the frame of each thread carrier is a supporting roller 27 which rests on disk 20. 10 At the outer end of the thread carrier frame are a pair of rollers 28, mounted in a horizontal plane and running in a groove 29 in frame 11. Said rollers 28 both support the outer end of the thread carrier and take the 15 centrifugal thrust as the carriers revolve. Another roller 30, mounted in a vertical plane at the outer end of the thread carrier frame, extends between rollers 18 and 19 (Fig. 3). The thread carriers are driven 20 from sleeve 4, through disk 13, and rollers 18, 19, engaging rollers 30, said rollers permitting the strands from the strand guides to be passed under the carriers and above 25 the rollers 18, 19, as the strands are carried over and under the thread carriers. The weight of the outer ends of the thread carriers is not supported by the rollers 18, 19, but by rollers 28 running in groove 29, and the rollers 18, 19, merely drive the thread 30 carriers. The outer end of each thread carrier frame is also provided on its upper side with another roller 31, lying in a horizontal plane and running between the frame 11 and a downwardly extending flange or guard 35 ring 32 secured to frame 11. Roller 31 acts in conjunction with rollers 28 to resist centrifugal thrust and cooperates with guard ring 32 to prevent the thread carrier from being dislodged inwardly from its position. 40 45 The threads t from the thread mass 26, and the strands t' which are passed over and under the thread carrier, all extend to the bushing 33, at the top of the hollow shaft 3, where the fabric is formed.

50 I claim:

1. In a braiding machine, a main revolving frame having an annular track, a revolving roller frame, means to drive said frames in opposite directions, a thread carrier supporting disk, a series of thread carriers, each having at the outer end a roller mounted to rotate in a horizontal plane and running in said annular track adapted to support the thread carrier at its outer end 55 and to receive centrifugal thrust, and also having at the inner end a roller mounted to rotate in a vertical plane and running on said thread carrier supporting disk, a roller mounted to rotate in a vertical plane at the under side of each thread carrier near its outer end, rollers arranged in pairs on radially disposed axes carried by said roller frame, adapted to engage the last named rollers on the thread carriers to drive the thread carriers in a circular path about the machine, 60

under side of each thread carrier near its 65 outer end, and rollers arranged in pairs on radially disposed axes carried by said roller frame, adapted to engage the last named rollers on the thread carriers to drive the thread carriers in a circular path about the 70 machine.

2. In a braiding machine, a main revolving frame having an annular track, a revolving roller frame, means to drive said frames in opposite directions, a thread carrier supporting disk, means to revolve said disk in the same direction as said main frame, a series of thread carriers, each having at the outer end a roller mounted to rotate in a horizontal plane and running in 80 said annular track adapted to support the thread carrier at its outer end and to receive centrifugal thrust, and also having at the inner end a roller mounted to rotate in a vertical plane and running on said thread carrier supporting disk, a roller mounted to rotate in a vertical plane at the under side of each thread carrier near its outer end, 85 and rollers arranged in pairs on radially disposed axes carried by said roller frame, adapted to engage the last named rollers on the thread carriers to drive the thread carriers in a circular path about the machine. 90

3. In a braiding machine, a main revolving frame having an annular track, a revolving roller frame, means to drive said frames in opposite directions, a thread carrier supporting disk, a series of thread carriers, each having at the outer end a roller mounted to rotate in a horizontal plane and running in said annular track adapted to support the thread carrier at its outer end and to receive centrifugal thrust, and also having at the inner end a roller mounted to rotate in a vertical plane and running on 100 said thread carrier supporting disk, a roller mounted to rotate in a vertical plane at the under side of each thread carrier near its outer end, rollers arranged in pairs on radially disposed axes carried by said roller frame, adapted to engage the last named rollers on the thread carriers to drive the thread carriers in a circular path about the machine, 105 a guard ring carried by said main frame and a roller mounted on the top of the thread carrier, engaging said guard ring to prevent the carrier from being dislodged inwardly. 110

4. In a braiding machine, a main revolving frame, a revolving roller frame for supporting one end of the thread carriers, and a revolving thread carrier supporting disk for supporting the other end of the thread carriers, means to drive said main frame and said disk in the same direction, and means to drive said roller frame in the opposite direction. 120

5. In a braiding machine, a stationary

central shaft, a sleeve rotatable on said shaft, a main revolving frame turning on said sleeve, means to drive said main frame and said sleeve in opposite directions, a roller frame fixed to said sleeve and turning therewith, a thread carrier supporting disk revolving on said central shaft, and radially

disposed pinions secured to said central shaft between said roller frame and disk, through which the disk is driven by and in 1 the opposite direction from the roller frame.

Signed by me at Boston, Massachusetts,
this 18th day of March, 1916.

ANKER PETERSEN.
